UNITED STATES PATENT OFFICE.

WARNER T. TABB, OF NEW YORK, N. Y., ASSIGNOR TO THE SAFETY CAR HEATING & LIGHTING COMPANY, A CORPORATION OF NEW JERSEY.

SIGNAL APPARATUS.

1,424,859.

Specification of Letters Patent. Patented Aug. 8, 1922.

Application filed May 5, 1917. Serial No. 166,673.

To all whom it may concern:

Be it known that I, WARNER T. TABB, a citizen of the United States, and a resident of the borough of Manhattan, in the city of New York, county and State of New York, have invented an Improvement in Signal Apparatus, of which the following is a specification.

This invention relates to signal apparatus and devices associated therewith, and more specifically to signal apparatus for railway-crossing gates.

One of the objects thereof is to provide practical signal apparatus of reliable and effective action. Another object is to provide means in connection with railway-crossing gates of such action as to give an effective warning at night. Another object is to provide an automatically acting valve of simple construction and dependable action. Other objects will be in part obvious and in part pointed out hereinafter.

The invention accordingly consists in the features of construction, combinations of elements and arrangement of parts which will be exemplified in the structure herein-after described, and the scope of the application of which will be indicated in the following claims.

30 In the accompanying drawings in which is shown one of various possible embodiments of this invention,

Figure 1 is a diagrammatic elevation of a railway gate and associated apparatus.

35 Figure 2 is an end view of a lamp and associated parts, this view being taken along the line 2-2 of Figure 1, and showing the parts on a large scale.

Figure 3 is a front view of the lower portion of the apparatus shown in Figure 2.

40 Figure 4 is a sectional elevation taken substantially on the line 4-4 of Figure 2, certain parts being omitted to show the construction more clearly.

45 Figure 5 is a sectional view taken along the line 5-5 of Figure 6, certain parts being removed in order to show the construction more clearly.

Figure 6 is a sectional view taken along the line 6-6 of Figure 2.

50 Figure 7 is a sectional plan taken along the line 7-7 of Figure 2.

Figure 8 is a front view of one of the lower members of Figure 2.

Figure 9 is a sectional view along the line 9-9 of Figure 8.

Figure 10 is a sectional elevation taken along the line 10-10 of Figure 2.

Figure 11 is a sectional view along the line 11-11 of Figure 10.

Figure 12 is a rear view of the parts shown in Figure 11.

Figure 13 is a sectional view taken along the line 13-13 of Figure 10.

Figure 14 is a detail view of a locking member.

Figure 15 is a cross section along the line 15-15 of Figure 14.

Figure 16 is a sectional view along the line 16-16 of Figure 10, certain parts being omitted.

Figure 17 is a sectional plan of a hinge cock.

Similar reference characters refer to similar parts throughout the several views.

Referring now to Fig. 1 of the drawings, there is shown at 20 a railway crossing-gate, and it may here be noted that this term is used throughout in a broad sense. This gate is pivotally mounted upon a pier or support 21 and is counter-balanced at 22 so as to swing upwardly as indicated by the arrow 23 upon being driven by the usual gearing and crank 24.

Mounted adjacent the gate is a tank 25 containing a supply of compressed combustible gas, the outlet 26 of which is controlled

as by a hand valve 27. From this point the gas passes through a pressure regulator 28 of the usual construction, and thence by means of the conduit 29 is led to the support 21.

Suitable bends in the conduit 29 lead the gas upwardly to a point in the axis about

which the gate swings, and then horizontally in alignment with such axis to a hinge cock, the parts of which are shown in Fig. 17 of the drawings.

The conduit 29 at its end is threaded within a tube 30 provided with an integral shoulder 31. This shoulder is fitted

within a sleeve 32 formed on a fitting 33 provided with a discharge port 34 which leads to a pipe 35.

Within the sleeve 32 is suitable packing 36 which is wedged against the inclined surface 37 of the shoulder 31 by means of a flanged collar 38 compressed by a

spring 39. These parts thus form a stuffing box or gland which makes a tight and secure

connection between the pipes 29 and 35 and

yet permits the pipe 35 with the fitting 33 to which it is secured to rotate about the axis of the tube 30 which is co-incident with the axis of the gate 20. The pipe 35 which extends along the gate 20 is thus permitted to swing freely without interrupting or weakening its connection with the supply tank 25.

Mounted upon the gate 20 and so disposed as to be in the most effective position when the gate is closed or in operative condition, is a lamp 40. The pipe 35 leads to this lamp and to render the construction more clear, it may be noted that it enters the lamp from 15 the right-hand side, as shown in Figure 3.

From the pipe 35 at its point of entry 41, the passage 42 leads, as best indicated in dotted lines in Fig. 6 of the drawings and in full lines in Fig. 5, to a short cross passage 20 43, these various passages being drilled out in the cast metal base portion of the lamp. From passage 43 the main supply passage 44 leads downwardly to an outlet 45 in the circular groove 46. The outer surface of 25 this depending portion 47 of the lamp base is provided with a pair of these concentric grooves, the outer one 48 of which leads through a suitable vent 49 to the main supply passage 50 from which point the course 30 of the main supply of gas will hereinafter be described in detail.

It may here be noted that the outer ends of these various passages are closed by suitable plugs as at 50°.

35 The base fitting of the lamp is mounted on the gate 20 by means of a suitable bracket 51 and secured to the depending portion 47 is a casing 52 of an automatic valve.

The function of this valve is to turn off 40 the main supply of gas as the lamp is swung upwardly into its inoperative position, and to turn it on as it is swung downwardly toward the roadway. This valve casing is secured to the part 47 by a single bolt or screw 45 53 in such manner as to permit it to be turned angularly about the axis of the screw for a purpose hereinafter described. The inner surface of the valve casing is provided with a pair of concentric grooves exactly 50 registering, with the parts assembled, with the grooves 48 and 46 hereinbefore referred to. The inner groove 54 on the valve casing is connected with a passage 55 as best shown in Fig. 16 of the drawings which terminates in a chamber 56. Threaded within the walls of this chamber is a valve fitting 57 having a passage 58 connected with the chamber 56 and leading to a suitable seat normally closed by a valve 59. This valve is 60 urged away from its seat by a coil spring 60 and its side walls are of such shape, the valve being of hexagonal cross section, that when it is withdrawn from its seat, the gas passes through the passage 58 and past the 65 valve into the interior of the valve casing.

From this space, that is the interior of the casing of this valve mechanism, the gas passes through a port 61 to the outer circular groove 62 and thence through the grooved recess 48 to the passage 50 as herein- 70 before described.

It will thus be seen that according as the valve 59 rests against its seat or is withdrawn from its seat, the main supply of gas is transmitted from the passage 44 to the 75 passage 50. This valve is automatically controlled by mechanism of the following nature:—The valve casing is provided not only with the fitting in which the chamber 56 is formed, but with an integral post 63 80 to which is hinged a swinging plate 64, shown in Figs. 14 and 15 of the drawings. This plate has threaded therethrough at 65 and secured in place by the nut 66 a pin 67, in the cup-shaped upper extremity of which is flexibly secured a pin 67. Pin 67 enters the hollow valve 59 and holds it against its seat in opposition to the spring 60. The angular position of the member 64 with respect to its axial pin 68, and consequently the position of the valve with respect to its seat, is determined by a pair of members 69 fitted within suitable openings 70 in the outer or free end of the swinging device. These members 69 are of tubular form and contain a suitable weight 71 which travels from end to end thereof as the gate is swung into or out of operative position. The weight 71 may be an amount of mercury, a metal cartridge, or a number of 100 metal balls. When the weight indicated in dotted lines at 71 is at the end of the tubes 69 remote from the member 64, the effect of gravity tends to swing the parts in such direction as to force the valve against its seat 105 and to cut off the main current flow of gas to the lamp. When however, the gate is lowered, the entire automatic valve swings with the gate and the weight at a certain point runs to the opposite end of the tubes 110 69 and at such time the effect of gravity swings the member 64 in the opposite direction, opens the valve 59, and permits the main current of gas to flow to the passage 50. 115

By the mounting of the automatic valve upon the base of the lamp by means of the screw 53 and by reason of the connection through the various concentric grooves, the angular position of the automatic valve with 120 respect to the gate may be adjusted at will with a corresponding adjustment of the gate angle at which the gas will be turned on to the lamp.

By the above means, the flow of gas to the 125 passage 50 is automatically controlled in accordance with the position of the gate. From the passage 50, the gas passes through a horizontal passage 72 in the lower wall 73 of the lamp base, and thence upwardly to a 130

valve seat 74. This lower portion of the lamp base forms a chamber 75, the top of which comprises a flexible resilient diaphragm 76 normally urged downwardly as 5 by a spiral spring 77. The diaphragm 76 is provided with a slotted post 78 as shown semi-diagrammatically in Fig. 4 of the drawings. Immediately beneath this post and between the valve seat 74 and a similar 10 valve seat 79 is a valve rocker pivoted at 80 and provided with a pair of valves 81 and 82, respectively co-acting with the valve seats 74 and 79. The rocker is always held in one of two alternative positions by 15 means of a short spring 83 stretched between the lowermost point of the rocker and a fixed pin 84 in such position that it snaps across the axis of the pivot 80 and is contracted as it moves either one or the 20 other of the valves against its seat. The slotted post 78 embraces loosely an arm 85 formed on the valve rocker. Assuming that the chamber beneath the diaphragm has become filled with gas, thus forcing the 25 diaphragm upwardly against pressure of spring 77, this action will throw the parts into the position shown in Fig. 4 of the drawings, with the valve 81 against the seat of the inlet passage, and the valve 82 away 30 from its seat 79. The gradual return of the diaphragm to normal position expels the gas through the valve seat 79 until the tripping post 78 comes into engagement with the arm 85 on the valve rocker and snaps 35 the latter into its opposite position with the inlet valve open and the outlet valve closed. This is repeated so long as the main supply of gas continues and results in an intermittent flow of gas outwardly through 40 the valve seat 79. It will also be seen that by suitable adjustment of the flashing mechanism and by throttling the inlet and outlet gas passages, the light and dark periods of the lamp may be regulated as desired. 45

From the valve seat 79 a passage 86 leads outwardly to a cross passage 87 which joins an upright passage 89. The passage 89 registers with a passage 90 in the upper portion of the lamp base which in turn leads 50 to the base of the burner tube 91 and thence to the burner.

In this manner when the gate is closed, there is a suitable supply of gas automatically turned on to the lamp and this supply 55 is fed to the burner intermittently, thus giving a correspondingly intermittent illumination or series of flashes which renders the signal much more effective at night.

In order to keep the light burning with a minimum consumption of gas, there is fed 60 to the burner or to a separate pilot burner, if desired, a continuous slight flow of gas whereby a small flame is always present and the main flow of gas instantly and automati-

cally ignited. This continuous flow is independent of the automatic valve and independent of the flashing apparatus and is preferably led direct from the passage 44 by means of a passage 92 to the passage 89. 70 There is preferably provided a small needle valve 93 controlling the passage 92 and controlled in turn by means of the screw 94.

The hood of the lamp is mounted on the burner tube 91, and is otherwise free from 75 connection with the base whereby it may be adjusted angularly about the axis of the burner tube and thus most effectively arranged with respect to the direction of traffic. The hood may be equipped with lenses 80 to direct the light along the line of street traffic, or otherwise a sign with the word "Stop" for example may be formed on the glass face of the hood and illuminated by a suitable reflector forming the opposite face 85 of the hood.

The body of the lamp is provided with suitable air inlet openings 99 in the upper portion of its base and with the customary chimney 96 at its upper end. 90

From the above description the action of the apparatus will be substantially clear. It may be noted that normally the gate is upwardly inclined or substantially vertical and that in this position the automatic valve, 95 by reason of the effect of gravity on the mercury, cuts off the main gas supply of the lamp. The pilot or small flame is however continuously supplied. When the gate is thrown downwardly into operative position, the main gas supply is turned on and the lamp immediately starts to flash its warning signal. This continues so long as the gate is in use, but when the latter is swung upwardly, the lamp is again automatically rendered inoperative. The gas in the tank is thus economically used, and due to its hinge connection with the conduit on the gate, a large heavy tank may be employed without in any way impeding the 100 action of the gate and without the chance of leakage. 105

It will thus be seen that there is provided apparatus in which the several objects of this invention are achieved and which is well suited to meet the requirements of the 110 hardest practical use.

As various possible embodiments might be made of the above invention and as various changes might be made in the embodiment above set forth, it is to be understood that all matter herein set forth or shown in the accompanying drawings is to be interpreted as illustrative and not in a limiting sense. 115 120

I claim as my invention:—

1. In apparatus of the class described, in combination, a crossing gate, means adapted to move said gate into and out of position, a source of light mounted on said gate, 130

means adapted to supply said source of light with energy for conversion into light, and a gravity actuated means mounted on said gate and adapted to control the flow of said energy from said supply means to said source of light thereby to render operative said source of light as said gate is moved into operative position and to render said source of light inoperative as said gate is moved into inoperative position.

2. In apparatus of the class described, in combination, a crossing-gate, means adapted to move said gate into and out of operative position, a gas lamp mounted on said gate, a source of gas supply, means adapted to turn on the gas to said lamp as said gate is moved into operative position and to turn off said gas as the gate is moved into inoperative position.

3. In apparatus of the class described, in combination, a crossing-gate, means adapted to move said gate into and out of operative position, a gas lamp, a source of gas supply, and means adapted to turn on the gas to said lamp as said gate is moved into operative position and to turn off said gas as the gate is moved into inoperative position, said lamp being mounted on said gate and said gas being turned on and off by movement of said gate.

4. In apparatus of the class described, in combination, a crossing-gate, means adapted to swing said gate into and out of operative position, a lamp mounted on said gate, a gas conduit leading substantially from the axis of said gate to said lamp, a source of gas supply, a gas conduit leading from said source of supply substantially to said axis, and a pair of relatively movable members substantially at said axis having a gas-tight joint therebetween and forming a passage from one to the other, one of said members being connected with one of said conduits and the other member being connected with the other conduit.

5. In apparatus of the class described, in combination, a crossing-gate, means adapted to swing said gate into and out of operative position, a lamp mounted on said gate, a gas conduit leading substantially from the axis of said gate to said lamp, a source of gas supply, a gas conduit leading from said source of supply substantially to said axis, a member having a passage substantially co-incident with said axis and connected with said second conduit, a member connected with said first conduit and mounted to swing with the same about said axis, said members being fitted one within the other, and resilient means urging said members together and forming between said members a gas-tight joint.

6. In apparatus of the class described, in combination, a crossing-gate, means adapted to move said gate into and out of operative

position, a gas burner mounted upon said gate, a source of gas supply, means adapted to connect said source of supply with said burner, and means adapted intermittently to vary the supply of gas to said burner.

7. In apparatus of the class described, in combination, a crossing-gate, a gas burner mounted on said gate, a source of gas supply, means forming a chamber having a resilient wall, a connection from said chamber to said source of gas supply, a connection from said chamber to said burner, and means adapted alternatively to render said connections operative.

8. In apparatus of the class described, in combination, a crossing-gate, means adapted to swing said gate into and out of operative position, a lamp mounted on said gate, a gas conduit leading substantially from the axis of said gate to said lamp, a source of gas supply, a gas conduit leading from said source of supply substantially to said axis, a pair of relatively movable members substantially at said axis having a gas-tight joint therebetween and forming a passage from one to the other, one of said members being connected with one of said conduits and the other member being connected with the other conduit, and means adapted to turn the gas to said lamp off and on according as said gate is moved into inoperative or operative position.

9. In apparatus of the class described, in combination, a crossing-gate, means adapted to swing said gate into and out of operative position, a lamp mounted on said gate, a gas conduit leading substantially from the axis of said gate to said lamp, a source of gas supply, a gas conduit leading from said source of supply substantially to said axis, a pair of relatively movable members substantially at said axis having a gas-tight joint therebetween and forming a passage from one to the other, one of said members being connected with one of said conduits and the other member being connected with the other conduit, and means adapted to turn the gas to said lamp on and off according as said gate is moved into operative or inoperative position, said last means being actuated by the swinging movement of said gate.

10. In apparatus of the class described, in combination, a crossing-gate, means adapted to move said gate into and out of operative position, a gas lamp, a source of gas supply, means adapted to turn on the gas to said lamp as said gate is moved into operative position and to turn off said gas as the gate is moved into inoperative position, said lamp being mounted on said gate and said gas being turned on and off by movement of said gate, and means adapted intermittently to vary the supply of gas to said source of light while said gate is in operative position.

11. In apparatus of the class described, in combination, a crossing-gate, means adapted to swing said gate into and out of operative position, a lamp mounted on said gate, a gas conduit leading substantially from the axis of said gate to said lamp, a source of gas supply, a gas conduit leading from said source of supply substantially to said axis, a pair of relatively movable members substantially at said axis having a gas-tight joint therebetween and forming a passage from one to the other, one of said members being connected with one of said conduits and the other member being connected with the other conduit, and means adapted intermittently to vary the supply of gas to said lamp while said gate is in operative position.

12. In apparatus of the class described, in combination, a crossing-gate, means adapted to swing said gate into and out of operative position, a lamp mounted on said gate, a gas conduit leading substantially from the axis of said gate to said lamp, a source of gas supply, a gas conduit leading from said source of supply substantially to said axis, a pair of relatively movable members substantially at said axis having a gas-tight joint therebetween and forming a passage from one to the other, one of said members being connected with one of said conduits and the other member being connected with the other conduit, and means adapted intermittently to flash said lamp while said gate is in operative position.

13. In apparatus of the class described, in

combination, a crossing-gate, means adapted to swing said gate into and out of operative position, a lamp mounted on said gate, a gas conduit leading substantially from the axis of said gate to said lamp, a source of gas supply, a gas conduit leading from said source of supply substantially to said axis, a pair of relatively movable members substantially at said axis having a gas-tight joint therebetween and forming a passage from one to the other, one of said members being connected with one of said conduits and the other member being connected with the other conduit, means adapted intermittently to vary the supply of gas to said lamp while said gate is in operative position, and means adapted to adjust the position in which said device becomes operative.

14. In apparatus of the class described, in combination, a crossing-gate, a lamp mounted on said gate, a source of gas supply, connections from said source of gas supply to said lamp, a valve in said connections, a supporting device mounted on said gate, a pivotally mounted member on said supporting device controlling said valve, a weight mounted on said member and movable with respect thereto to swing said member, and a mounting for said supporting device adapted to permit it to be adjusted to vary the time of action of said weight with respect to the position of said gate.

In testimony whereof, I have signed my name to this specification this 2nd day of May, 1917.

WARNER T. TABB.
